(57) **CLAIM**

The ornamental design for an adjustable armature including pivotable knuckle, as shown and described.

DESCRIPTION

FIG. 1 is a perspective view of an adjustable armature including pivotable knuckle, showing our new design;
FIG. 2 is a front elevation view thereof;
FIG. 3 is a back elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is another perspective view thereof;
FIG. 9 is a reduced in scale perspective view showing in a usage condition; and,
FIG. 10 is another perspective view thereof.

The broken lines shown in the drawings illustrate the portions of the Adjustable Armature Including Pivotable Knuckle that form no part of the claimed design, further the broken lines shown in the FIGS. 9 and 10 illustrate an unclaimed environment and none of the broken lines form any part of the claimed design.
